[57] CLAIM

The ornamental design for a radiotelephone housing, as shown and described.

DESCRIPTION

FIG. 1 is a front, top, and left side perspective view showing of our new design for a radiotelephone housing in a closed position.

FIG. 2 is a front, top, and left side perspective view showing the radiotelephone housing of FIG. 1 in an open position.

FIG. 3 is a rear elevation view thereof.

FIG. 4 is a right side elevation view thereof.

FIG. 5 is a bottom plan view thereof.

FIG. 6 is a front, top, and left side perspective view showing an alternate embodiment of our new design for a radiotelephone housing in a closed position.

FIG. 7 is a front, top, and left side perspective view showing the radiotelephone housing of FIG. 6 in an open position.

FIG. 8 is a rear elevation view thereof.

FIG. 9 is a right side elevation view thereof.

FIG. 10 is a bottom plan view thereof.

FIG. 11 is a right side elevation view showing the radiotelephone housing of FIG. 9 in an open position.

FIG. 12 is a bottom plan view showing the radiotelephone housing of FIG. 10 in an open position; and,

FIG. 13 is a rear elevation view showing the radiotelephone housing of FIG. 8 in an open position.

The broken line matter in the drawings is for illustrative purposes only and forms no part of the claimed design.
